ALFRED VISCHER, JR., OF RIDGEWOOD, NEW JERSEY, ASSIGNOR TO THE FINANCIAL PRESS COMPANIES OF AMERICA, OF BOSTON, MASSACHUSETTS, A TRUST OF MASSACHUSETTS

DESIGN FOR A NEWS TICKER CASING OR STAND

Application filed April 2, 1932. Serial No. 43,366. Term of patent 14 years.

To all whom it may concern:

Be it known that I, ALFRED VISCHER, Jr., a citizen of the United States, residing at Ridgewood, in the county of Bergen and State of New Jersey, have invented a new, original, and ornamental Design for a News Ticker Casing or Stand, of which the following is a specification, reference being had to the accompanying drawing, forming a part hereof.

ticker casing or stand embodying the new design;

Figure 2 is a plan view of the ticker casing or stand embodying the new design, and

I claim:

The ornamental design for a news ticker casing or stand, as shown.

ALFRED VISCHER, JR.
